Application October 17, 1935, Serial No. 45,414

9 Claims. (Cl. 242—76)

This invention relates to a device for holding coiled material and, in particular, coiled strip material, although it has other applications as well.

5 In the manufacture of steel strip, after hot rolling, the partly reduced strip is coiled for delivery to various points for subsequent processing. In the subsequent processing, e. g., pickling, the coiled hot rolled strip must be unwound and passed through the treating apparatus in 10 strand form. The particular object of the present invention is to provide means for supporting a coil of such strip while being unwound for subsequent processing.

15 Holders for coiled strip material of various kinds have been known heretofore. In one such device, a pair of centering heads are disposed on a common actuating screw coaxial therewith. One of the heads must be removed from the screw, however, to permit a coil to be slipped over the end of the latter. This arrangement is not satisfactory for the purpose described above because of the difficulty in positioning the coil on the support. Other forms of coil holders have 20 therefore been developed, specifically, a device including a pair of movable standards, each having a centering head projecting toward the other, and a common screw for adjusting the standards toward and away from each other, the screw being journaled in a suitable base and parallel to but spaced from the axis of the heads. When the hot rolled strip has not been coiled accurately, because of camber in the strip, or for some other reason, it is desirable to try to remedy the condition by drawing the centering head together. Since 25 the screw which effects this result is off-center with respect to the axis of the heads, the supporting standards tend to tilt, permitting the centering heads to depart from a true coaxial relation, and as a result the centering heads bind the coil between them and prevent unwinding.

We have invented a coil support which overcomes objections to the types aforementioned, in that it includes spaced centering heads having 30 a free space therebetween, whereby a coil can be moved into coaxial relation therewith from points laterally of the axis of the heads. The heads are adjustable toward and away from each other and the means for causing such adjustment is coaxial with the heads, so that there can be no misalignment of the latter or binding of the coil between them. In addition, we provide means for lifting a coil into position between the heads and turning it to the desired 35 position for starting the unwinding. A fur-

ther feature of our invention is the provision of means for adjusting the coil axially in case the strip being delivered therefrom tends, because of camber therein or for some other reason, to depart from the desired direction of delivery. Such means automatically maintains the strip coming off the coil in a predetermined delivery line, which facilitates its passage through various treating apparatus, such as pickling and washing baths and the like.

5 In order to cause corresponding adjustment of each centering head, we provide means, preferably electrical for tying together the adjusting means therefor. Independent adjustment of the two heads is also permitted.

10 A present preferred embodiment of the invention is illustrated in the accompanying drawings from a consideration of which together with the following detailed description, a complete understanding thereof can readily be obtained.

15 In the drawings—

Figure 1 is a diagrammatic side elevation; Figure 2 is a view partly in section and partly in elevation, to enlarged scale, of a portion of the apparatus shown in Figure 1;

20 Figure 3 is a partial sectional view along the line III—III of Figure 2;

Figure 4 is a circuit diagram showing one form of automatic control system;

25 Figure 5 is another circuit diagram showing a further form of control system; and

Figure 6 is a diagrammatic view illustrating a detail of the automatic control system.

30 Referring now in detail to the drawings and, for the present, to Figures 1 through 3, standards 35 10 are mounted in spaced relation on a suitable foundation 11. Each standard has spaced bearings 12 through which a tubular thrust member 13 is axially slidable. A trunnion 14 is secured to the inner end of each thrust member and is provided with a head 15 rotatably mounted thereon by anti-friction bearings 16. Each head 15 has a coil engaging flange or disk 15a. The heads 15 have rearward extensions 17 serving as brake drums. Brake bands 18 disposed about the extensions 17 are secured to the trunnions by links 19 for exerting an adjustable force retarding rotation of the heads. Each head is provided with a plurality of collars 20 of graduated sizes whereby the heads can be accommodated to coils having central openings of different diameters.

45 Each of the thrust members 13 has an adjusting screw 21. The inner ends of the screws 21 are journaled in thrust bearings formed in webs 22 extending across the thrust members. The other 50

ends of the screws are coupled to the shafts of dynamo-electric machines 23 and 23' carried on shelves 24 attached to the outer ends of the thrust members.

5 Each thrust member has a longitudinal slot 25 therein. A projection 26 extends upwardly from each standard 10 through the slot 25 and carries a nut 27 through which the screw 21 is threaded. A dynamo-electric machine 28 may be disposed 10 on one of the shelves 24 and coupled, for example, to the machine 23 for a purpose which will appear hereinafter.

A lifting saddle 29 is disposed in a pit 30 between the standards 10 and comprises a base 31 15 mounted on screw jacks 32 and adapted to be raised or lowered thereby. A pair of spaced coil supporting rolls 33 are journaled on the base 31 in suitable bearing posts 34. A motor 35 is mounted on the base 31 for driving one of the rolls 20 33 through a chain sprocket connection 36. A motor 37 mounted between the screw jacks 32 drives them through worm and worm wheel reduction gears 38.

The operation of the apparatus so far described 25 will now be briefly reviewed. The centering heads 15 are normally retracted by suitable operation of the screws 21. A coil to be supported for unwinding is then deposited, by means of a crane, for example, on the saddle 29 which is normally 30 in its lowermost position. The coil is indicated diagrammatically at 40. After the coil has been deposited on the saddle, the latter is raised by operation of the motor 37 until the opening through 35 the coil is substantially in line with the axes of the centering heads. The motor 35 can then be operated to turn the coil slightly one direction or the other if necessary, in order to position the outer end properly for entry into the treating apparatus. The centering heads are then advanced toward the coil by means of the screws 21. 40 The heads 15 and the collars 28 disposed thereabout are slightly tapered to facilitate their entry into the ends of the openings through the coils. When the coil 40 has been properly engaged by 45 the heads 15, the base 31 of the saddle is lowered and the coil is then free to turn as a strip is unwound therefrom.

Movement of the heads 15 inwardly or outwardly may easily be obtained if the machines 23 50 and 23' are either direct or alternating current motors, by suitable control mechanism, an example of which is illustrated in Figure 4. If it is desired to adjust the heads 15 simultaneously and precisely to the same extent, they may be tied 55 together electrically if the machines 23 are wound rotor induction machines suitably connected, the motor 28 serving to drive the machine 23 as a generator, the machine 23' operating as a motor and moving in synchronism with the machine 23.

60 This system is illustrated in Figure 5. Referring now to Figure 4 wherein the machines 23 and 23' are assumed to be alternating current motors, for example, induction motors, a three-phase supply circuit is shown at 41. Current is supplied to the motors 23 and 23' through a manual switch 42 and a main line contactor 43.

The circuit to the motors includes the back contacts of the reversing switches 44 and 45. The contactor 43 may be closed by a push button 46. 65 The motors 23 thereupon turn in the same direction, for example, in such direction as to cause the shafts 21 to move the centering heads inwardly. If it is desired to move the centering heads outwardly, a push button 47 causes the simultaneous energization of the contactor 43 and

reversing switch 44. The latter reverses the connections between two of the phases of the supply circuit and the motors 23 and 23'. The latter will then rotate in the reverse direction to cause outward movement of the centering heads. If it is desired to cause both heads to move to the right, a push button 48 permits simultaneous energization of the main contactor 43 and the reversing switch 45. This connects the motor 23 in a direction such as to cause the left hand centering head to move to the right. The motor 23' is connected for rotation in the reverse direction through the front contacts of the reversing switch 45 and the back contacts of a reversing switch 46. The motors rotate in opposite directions and both the heads move toward the right.

If it is desired to cause both the heads to move to the left, a push button 50 makes this possible. The push button 50 energizes the main contactor 43, the reversing switches 44, 45 and 46. 20 The reversing switch 44 reverses the motor 23 causing the left hand head to move toward the left. The reversing switch 45 operates in the usual manner to reverse the motor 23', but the reversing switch 46 is effective to reverse the connections again, restoring them to the normal condition for forward rotation so that the right hand head also moves to the left.

If it should happen that the strip is not coiled accurately, because of camber therein or for 30 some other reason, it will tend to depart from the perpendicular to the coil axis as it unwinds. This is objectionable because the strip does not follow a predetermined path through the treating apparatus. We compensate for any such 35 departure of the strip from its normal path by means of contacts 51 and 52 adapted to be closed respectively, when the strip shifts to the right or left as viewed in Figure 4. Closure of the contacts 51 as a result of the strip swinging to 40 the right causes the push button 50 to be closed by energizing a closing coil 53. As before described, this causes the motors 23 and 23' to move the coil 40 to the left, restoring the strip to its proper position. Conversely, closure of the contacts 52 energizes a closing coil 54 for the 45 push button 48 to cause reverse adjustment of the centering heads.

If the motors 23 and 23' are similar in size and construction, they will under normal conditions operate substantially in step, if not in exact synchronism. Simultaneous energization of the motors will cause approximately the same 50 adjustment of the two screws 21. If it is desired that the screws be positively locked together, the system of Figure 5 is employed. In this system, the machines 23 and 23' are wound rotor induction machines, the machine 23 operating as a generator and the machine 23' operating as a motor connected thereto so as to 55 rotate therewith. The motor 28 serves to drive the generator 23 and by certain connections to be described later, the generator 23 causes the motor 23' to follow it in exact synchronism, just as if the two screws 21 were mechanically connected.

A main supply source is indicated at 60. A main contactor 61 connects the motor 28 to the supply 60 through the back contacts of a reversing switch 62 in such direction as to cause forward rotation of the motor 28 to turn the left hand screw 21 and adjust the left hand head 15 inwardly. The stator winding of the machines 23 and 23' are connected in parallel with the motor 28 which is preferably an induction 70

75

motor. The rotor on the generator 23 is connected through slip rings and conductors 63 to the rotor of the machine 23'. The connection for the stator of the machine 23' includes the 5 back contacts of a reversing switch 64.

Closure of the contactor 61 can be effected by operation of a push button 65. This energizes the motor 28 in a forward direction and adjusts the left hand head inwardly. The machine 10 23 being driven by the motor 28 operates as a generator, while the machine 23' operates as a motor and keeps in exact synchronism with the movement of the generator 23. Both screws 15 21 are thus adjusted inwardly simultaneously and to precisely the same extent.

If it is desired to adjust both centering heads outwardly, it is only necessary to reverse the direction of rotation of the motor 28. This is done by the reversing switch 62. A push button 20 66 permits the main contactor 61 and reversing switch 62 to be simultaneously energized for reverse operation of the adjusting screws.

If it is desired to move both centering heads to the right, the connections to the stator of the machine 23 must be reversed with respect to those of the machine 23'. This is accomplished by the reversing switch 64. A push button 67 permits simultaneous operation of the contactor 61 and the switch 64. When the push button 67 is operated, the motor 28 operates in a forward direction, while the motor 23' operates in the reverse direction. Both adjusting heads thus move to the right. If it is desired to move both heads to the left, this is accomplished by reversing the rotation of the motor 28 and also the connections of the motor 23'. A push button 68 permits simultaneous energization of the contactors 61, the reversing switch 62 for the motor 28 and the reversing switch 64 for the motor 23'. When the push button 68 is operated, the motor 28 operates in a reverse direction, while the motor 23 operates in a forward direction, causing both centering heads to move to the left.

45 Automatic operation of the push buttons 67 and 68 in accordance with the departure of the strip from a predetermined path is effected as in Figure 4 by contacts 51 and 52.

It will be understood that the control apparatus and the circuit diagrams shown in Figures 50 4 and 5 are illustrative only and are not intended to limit the invention. The particular circuits shown have been employed because they illustrate simply the theory in view, and while the systems shown will operate satisfactorily, modifications or additional refinements will suggest themselves to those skilled in the art of electrical control.

60 It will be apparent from the above description that the invention provides a novel and highly useful form of coil support, the chief advantages of which are that the force effective to adjust the centering heads inwardly and outwardly is applied coaxially thereof, so as to prevent misalignment of the heads and binding of the coil therebetween. In addition, the invention lends itself readily to automatic control of the centering heads to maintain the delivered strip in a predetermined path. Any departure of the strip from this path is immediately compensated for by the contacts controlled by the strip edges. It is thus possible to feed a strip continuously 65 along a given path regardless of camber in the

strip or improper coiling thereof. The centering heads may be adjusted independently or they may be tied together electrically as described.

Although we have disclosed herein but one form 5 of our invention, it will be recognized that changes therein may be made without departing from the spirit of the invention or the scope of the appended claims.

I claim:

1. A coil support comprising a standard, a thrust member axially slidable thereon, a centering head on said member, an adjusting screw journaled on said member, and a nut on said standard cooperating with said screw, and a 15 second centering head adapted to cooperate with the first mentioned head.

2. A coil support comprising a standard, a thrust member axially slidable thereon, a centering head on said member, an adjusting screw 20 journaled on said member coaxially with said head, and a nut on said standard cooperating with said screw, and a second centering head adapted to cooperate with the first mentioned head, said screw being coaxial with said second 25 head.

3. A coil support comprising a standard, a thrust member axially slidable thereon, a centering head on said member, an adjusting screw journaled on said member, and a nut on said 30 standard cooperating with said screw, a second centering head adapted to cooperate with the first mentioned head, and power means on said member for driving said screw.

4. Coil supporting apparatus comprising a 35 standard, a tubular thrust member slidable therethrough, a centering head on said member, a screw journaled coaxially with said head and member, a longitudinal slot in said member, a projection from said standard extending through 40 said slot, a nut on said projection cooperating with said screw, and a second centering head cooperating with said first mentioned head.

5. The combination with a pair of spaced centering heads, means for adjusting said heads axially, a motor for driving the adjusting means of one of said heads, and an electrical tie between the adjusting means of the two heads. 45

6. The combination defined by claim 5 characterized by said tie comprising a generator driven 50 by said motor, and a motor connected to the generator for driving the adjusting means of the other of said heads.

7. A coil support including a trunnion, a centering head rotatable thereon, a thrust member to 55 which said trunnion is secured, means whereby said member is slidably but non-rotatably mounted, a fixed nut, a screw in said member cooperating with said nut and means on said member for driving said screw.

8. Coil handling apparatus comprising a pair 60 of spaced centering heads adapted to engage a coil, a motor for operating each head, and a generator driven by the motor of one head, and means for connecting the generator to the motor of the other head.

9. A coil support comprising a pair of spaced centering heads, and means for moving each head axially including a driving motor, a generator driven by the motor of one head, and means for connecting the generator to the motor of the other head. 70

RAYMOND J. WEAN.
DONALD A. McARTHUR.
